T. A. BERGIN

COMBINATION GUN BARREL AND GAS TRAP

Filed Feb. 29, 1924

Inventor

Thomas A. Bergin,
By Edward E. Clement
Attorney

UNITED STATES PATENT OFFICE.

THOMAS ALOYSIUS BERGIN, OF WICHITA FALLS, TEXAS.

COMBINATION GUN BARREL AND GAS TRAP.

Application filed February 29, 1924. Serial No. 696,033.

To all whom it may concern:

Be it known that I, THOMAS ALOYSIUS BERGIN, a citizen of the United States, residing at Wichita Falls, in the county of Wichita and State of Texas, have invented certain new and useful Improvements in Combination Gun Barrels and Gas Traps, of which the following is a specification, reference being had therein to the accompanying drawing.

My invention relates to gas traps and more particularly to means for the separation of the gas and water from oil as it is taken from wells. It is the object of my invention to provide a combination gun barrel and gas trap in which the trap is combined with an overflow pipe arrangement whereby the gas which accumulates in the tank may be led off and used for fuel or other purposes and whereby the operator of the tank is enabled to see the oil from each well as it runs into the tank.

My invention consists in the construction and novel arrangement of parts hereinafter fully described, and illustrated in the accompanying drawing, in which the figure is a vertical sectional view of the apparatus.

A is a tank, preferably constructed of 10 gauge Keystone copper steel and may be bolted, riveted or welded and of any size and weight, as required. It is cylindrical in form, ordinarily about 16 feet high and 6 feet in diameter. The tank is equipped with a clean-out plate, a ; a 2-inch flange, a' ; a 3-inch bleeder, a^2 ; a pressure valve, a^3 and an opening flange E. It is also equipped with a 3-inch overflow pipe inside the tank marked C. This overflow pipe has a T in the bottom marked C' with a plug c^2 turned down, connected to the 3-inch flange c^1 in the bottom of the tank, for draining of the pipe, testing the oil, or letting out any water that may enter the pipe. This pipe leaves the tank at the flange c' and on the outside of the tank is connected to a 3-inch T marked c^4 . A conductor pipe B runs down the center of the tank near the top of which are located opposite each other two 2" swing check valves D. In the top of the conductor pipe is a man-hole dome b, a man-hole cover b' and a cast iron cover or 8-inch plug b². The conductor and overflow pipe are braced to the inside of the tank as shown at F. The connections marked B' can be made of 2-inch or 3-inch flanges as this is the point where the pipe

lines running from the wells will enter the tank.

In operation the oil from the wells is conducted to the flanges B' as described and is thence conducted into the tank through the conductor B. The check valves are for the purpose of allowing the gas to escape from the conductor into the tank and are preferably located about one foot and a half from the top of the tank. The oil rises in the tank to the top of the overflow pipe at c^6 and is from there conducted through said overflow pipe to the stock tanks. After the oil enters the tank the only gas that escapes is that portion in the conductor pipe from the oil level to the thief hole b^2 and that portion only when the operator opens b^2 to see the wells pumped. The other gas having gone through the check valve is held under pressure. The overflow pipe is preferably about 3 inches in diameter, and is installed inside of the tank in order that nothing but oil will reach the stock tank and also to insure against the pipes parafining up, and against the gas pressure, being confined in the tank from siphoning the tank into the stock tanks. Should the pressure above the oil level force the oil below the normal level in the flow tank, no oil can escape said tank until sufficient new oil has entered the tank to offset the gas pressure above. The flange a is for the purpose of a water siphon which may be adjusted to suit the operator. The bleeder marked H is installed as a precautionary measure and can be used in case the operator should allow the water level to reach the top of the overflow pipe, in which case the water can be drained out of the pipe thereby. The 3-inch T, marked c^5 on the outside of the tank connected at the flange c^4 is to enable the operator to blow out or clean out the overflow pipe. The gas is led off from the tank at the flange opening E.

From the above description it is apparent that the device though simple in its construction will perform its function which is three fold, the separation of the gas, the water and the oil, and the leading of each of these off through different outlets, in a highly efficient manner. The combination of the gas trap with the overflow pipe in the manner described is believed to be novel and original with me and will be claimed accordingly. It is to be understood however that I do not limit myself to any

as fairly fall within the scope of the invention and of the claims appended hereto.

5. What I claim is:

1. A combined gun barrel and gas trap for separating gas, water, and oil, comprising a tank, means for conducting the oil from the wells down through said tank, 10 means associated with said conductor for trapping the gas therefrom in the tank, and an overflow pipe member for leading off oil from an intermediate level in the tank, together with means in the upper part and 15 means in the lower part of said tank for leading off gas and water respectively therefrom.
2. A combined gun barrel and gas trap for separating gas, water, and oil as taken 20 from a well, comprising a tank, a conductor pipe therein passing down the center thereof, a pair of gas traps arranged opposite each other in the upper part of said conductor, a U shaped overflow lead-off pipe 25 for the oil, and means located in the upper and means in the lower part of said tank for leading off gas and water respectively.
3. In an apparatus for separating gas and water from oil, a tank, a conducting member 30 passing downwardly inside and to the bottom of said tank, means arranged on said conductor for trapping the gas therefrom into the tank, an overflow pipe member adapted to lead off the oil from an intermediate level in the tank, means above and 35 means below said level for leading off gas and water respectively and a removable closure in the lower part of said tank for draining the same.
4. In an apparatus for separating gas and water from oil, a tank, a conducting member passing downwardly to the bottom of said tank, means arranged on said conductor for trapping the gas therefrom into the 40 upper part of the tank, an overflow pipe member arranged in the lower half of said tank, adapted to lead off the ~~said~~ oil from an intermediate level, a downwardly turned drainage member arranged in the lower part of said overflow pipe, leading through

the part and means in the lower part of said tank for leading off gas and water respectively.

5. In an apparatus for separating gas and water from oil, a tank, a conducting member therein passing downwardly to the bottom of said tank, means arranged on said conductor for trapping the gas therefrom into the upper part of the tank, an overflow pipe trap in the lower part of said tank to lead off the said oil from an intermediate level, a T member located on the lowest part of said pipe to enable the operator to blow out the same, and means in the upper and 65 means in the lower part of said tank for leading off gas and water respectively.

6. In an apparatus for separating gas and water from oil, a tank, a conducting member therein passing downwardly inside 70 and to the bottom of said tank, means arranged on said conductor for trapping gas therefrom into the upper part of said tank, an overflow pipe adapted to lead off the said oil from an intermediate level in the tank, 75 means in the upper part and means in the lower part of the tank for leading off gas and water respectively and a pressure valve arranged in the upper end of the tank.

7. In an apparatus for separating gas and water from oil and for conserving the gas and low gravity vapors, a tank, a conducting member leading downwardly through said tank, with an opening at the bottom end thereof for passing oil therefrom into 80 the tank, and means for trapping gas therefrom into the tank, intake means at the upper end of said conducting member outside the tank, and an observation opening or thief hole in the conducting member adjacent said intake means together with gas retaining means for drawing off oil from an intermediate level in the tank, means for drawing off gas above said oil level, and means for drawing off water below said oil 85 level.

In testimony whereof I hereunto affix my signature.

THOMAS ALOYSIUS BERGIN.
